INVENTOR
Sheldon M. Booth,
BY Charles Turner Brown,
ATTORNEY.

UNITED STATES PATENT OFFICE.

SHELDON M. BOOTH, OF CHICAGO, ILLINOIS.

MEANS TO WITHDRAW SURFACE WATER FROM BATHING BEACHES AND RESORTS.

Application filed June 20, 1922. Serial No. 569,684.

To all whom it may concern:

Be it known that I, SHELDON M. BOOTH, a citizen of the United States, and a resident of Chicago, in the county of Cook and State of Illinois, have invented certain new and useful Improvements in Means to Withdraw Surface Water from Bathing Beaches and Resorts, of which the following, when taken in connection with the drawing accompanying and forming a part hereof, is a specification.

This invention relates to means for preserving the cleanliness of water at a bathing beach or resort where many persons are in the water.

The invention is based on the assumption that where a large number of persons are disporting and bathing in water having no appreciable current the surface of the water becomes contaminated and infection to the mouth, throat and face of persons is incurred.

Among the objects of the invention is to maintain the surface water at a bathing beach or resort where no observable current or flow exists, clean and wholesome, so that infection of any kind will not occur. An additional object of the invention is to obtain means by which the surface water may be maintained in a cleanly condition without producing currents of water which are dangerous to persons bathing or disporting therein; and further to obtain means to maintain the surface water clean in a manner which will obviate injury to persons in the water by coming in contact with any part of the mechanism of the installation made. Additional objects are to obtain means by which the surface water over a large area will be maintained in a cleanly condition, and without special care; which is economically constructed and installed, and not liable to get out of order or break down.

In the drawing referred to Fig. 1 is a vertical section of a bathing beach, showing an installation of the means embodying this invention for maintaining the surface water thereon in a cleanly condition, with the surface of said water indicated by broken lines.

Fig. 2 is a top plan view of said installation, showing a section of the shore line and beach, the water and beach thereunder not being illustrated.

And Fig. 3 is a vertical section of a well positioned on the shore of the bathing

beach, showing mechanism installed therein, on an enlarged scale.

A reference character applied to designate a given part indicates said part throughout the several figures of the drawing, wherever the same appears.

A represents the ground of the bathing beach, above and below the water line. B indicates the usual or normal water level on the beach. C, (Fig. 1), represents a sewer and C' the normal level of water in said sewer. D represents a well through which access is had to sewer C, and d the cover to the sewer well D. E represents a well which is positioned adjacent to the shore line of the beach, and F represents piping which extends from near the bottom of well F to underneath the bottom of the bathing beach, said piping being embedded in the ground forming the bottom thereof. G, g, g', g'' represent branch piping which extends from piping F and is in communication therewith, said piping G, g, g', g'', being also embedded in the ground underneath the water on the beach. H, H, represent stand pipes which communicate, at the lower ends thereof, with the several branch pipes G, g, g', g'', and which extend above the normal surface of the water on the beach, (indicated as recited, by broken line B), to be exposed to view; and h, h, represent dome like covers on the upper ends of stand pipes H, H, respectively. I, I, indicate apertures in stand pipes H, H, and covers h, h. It will be observed that the apertures I, I, in the stand pipes H, H, extend a short distance down said stand pipes from the upper ends thereof, so that only water near the surface of the water on the beach can flow into said stand pipes, said apertures determining the depth to which water will be taken from the beach. The extension of the stand pipes H, H, above the normal level of the water on the beach, and providing apertures in said stand pipes and in the covers thereof, serves the double function of apprising persons in the water of the location of said stand pipes, and permits a larger flow of water into said stand pipes.

J. represents a stand pipe in well E, and K a pipe from the upper end of stand pipe J to the sewer C, said pipe K communicating with stand pipe J, and with the sewer below the normal level of the water in said sewer. The pipe F, hereinbefore described,

- communicates with stand pipe J, when the gate L is open, and is shut off from said communication when said gate is closed. 5
l represents a rod by means of which the position of gate L is controlled. M represents an air cock which is positioned on the upper end of stand pipe J, and m a removable bottom on the lower end of said stand pipe.
- 10 N, Fig. 3, represents a pump, which is preferably a centrifugal pump, and is so illustrated, in stand pipe J. O represents a bevel gear, which is rigidly mounted on the rod or shaft n of pump N, near the upper end thereof. P represents an electric motor, mounted on shelf Q, and p a bevel gear on the shaft of motor P which intermeshes with bevel gear O on the pump shaft n.
- 15 20 In cases where a sewer is embedded or positioned at a sufficient depth in the ground, as in Fig. 1, to receive and dispose of water flowing from pipe K, a pump in pipe J is not required, as water flowing into said stand pipe J from pipe F will rise in said stand pipe, and by opening the air cock M, to permit air in said stand pipe to be forced therefrom, and thereafter closing said air cock, a siphon flow of water up the stand pipe and through the pipe K to sewer C will be obtained; it being understood that the end of said pipe K which discharges into said sewer is below the level of the water flowing through the sewer, as is illustrated in Fig. 1. Where the sewer into which pipe K discharges is not positioned below the apertures I, I, in stand pipes H, H, and the above recited siphon flow can not be obtained, the pump N is operated, by motor P, or by other suitable means, and the water discharged into stand pipe J is forced upward therein and discharged therefrom into pipe K, and from thence to a sewer.
- 25 30 35 40 45 50 55 60 65 70 75 80 85 90 95 The several branch pipes G, g, g', g'', are of different diameters, being designed to convey the quantity of water which it is desired to have flow therethrough to pipe F, so that each of the several stand pipes H, H, will at all times discharge a substantially uniform quantity of water into the branch pipe with which it communi-
- cates, and pipe F is of a diameter relative to the diameter of branch pipes G, G, to receive and convey to the stand pipe J all the water discharged thereinto from the pipes G, G.
- All the several pipes are of sufficient diameter to obtain the required flow of water through the apertures I, I, to effect the removal of infected water from the beach and to maintain the water on the beach clean and wholesome, and render the beach safe for bathing purposes by a large number of persons.
- X indicates a flood gate, to prevent flow of water from the sewer into pipe K.
- I claim;
1. A bathing beach installation comprising stand pipes provided with apertures adjacent to the upper ends thereof, pipes embedded in the bottom of the beach and communicating with said stand pipes, an additional stand pipe with which and near the lower end thereof said embedded pipes communicate, a gate arranged to control the flow of water into said last named stand pipe, and means to create an upward flow of water in said last named stand pipe and the discharge of water therefrom at the upper end thereof, all combined as set forth.
2. A bathing beach installation comprising stand pipes provided with apertures adjacent to the upper ends thereof, said stand pipes extending above the normal level of water on the beach, and dome shaped covers respectively provided with apertures mounted on said stand pipes, pipes embedded in the bottom of the beach and communicating with said stand pipes, an additional stand pipe positioned on the beach, with which, and near the lower end thereof, said embedded pipes communicate, a gate arranged to control the flow of water into said last named stand pipe, a pump, and means to actuate said pump, to force an upward flow of water in said last named stand pipe and the discharge of said water from the upper end of said stand pipe, all combined as set forth.

SHELDON M. BOOTH.
